UNITED STATES PATENT OFFICE.

GEORGE W. HUGHES, OF ROCHESTER, NEW YORK, ASSIGNOR OF ONE-HALF
TO HAMLET S. BRIGGS, OF SAME PLACE.

HANDLE FOR UMBRELLAS, PARASOLS, AND CANES.

SPECIFICATION forming part of Letters Patent No. 250,328, dated November 29, 1881.

Application filed October 11, 1881. (No model.)

To all whom it may concern:

Be it known that I, GEORGE W. HUGHES, of Rochester, Monroe county, New York, have invented a certain new and useful Improvement 5 in Umbrellas, Parasols, and Canes; and I do hereby declare that the following is a full, clear, and exact description of the same, reference being had to the accompanying drawings, in which—

10 Figure 1 is an elevation showing my improvement applied to an umbrella-handle. Figs. 2 and 3 are section views of the same, showing the spring-arm respectively in the closed and the open position. Fig. 4 is an elevation of the notched ferrule which holds the spring-arm.

15 My invention consists of a spring-arm resting in a cavity or socket of the umbrella or parasol handle, and provided with a rubber or other soft pad at its outer end, and so arranged, as hereinafter described, that it can be swung out at an angle, and serve in that position to hang the article upon a counter, desk, seat, or other support, as hereinafter more fully described.

20 In the drawings, A represents the handle of an umbrella or parasol.

B is a metallic arm, having a lug, a, on its under side, through which passes a pivot, b, that fastens it to the handle but allows it to swing out and in. When swung out to the proper angle, as shown in Fig. 3, it stiffens, and in that condition its lower end can be hung upon a counter, desk, table, or other support, or hung upon a hook, thereby sustaining the umbrella or parasol. When turned in, as shown in Fig. 2, the arm closes into a socket or cavity, e, formed to receive it in the wood, and it then lies flush with the exterior surface 40 of the handle. On the outer or lower end of the arm is a rubber or other soft pad, d, which rests upon the counter or other support, thereby preventing scratching or marring the surface of the support, and also producing friction, so that the arm will not readily lose its hold.

45 On the under side of the arm is a spring, f,

of any suitable kind, the object of which is to throw the free end of the arm outward when released from its holding catch. In the drawings a flat spring is shown, but any other kind may be employed; or, if desired, the arm itself may be made of a spring and in one piece.

50 g is a ferrule resting around the handle and covering the end of the arm when closed. In 55 the ferrule is made a notch, h, of such size that when it is turned around in coincidence with the arm it will allow the arm to pass out through the notch. When the notch is turned around away from the arm the latter is held firmly 60 closed. If desired, the ferrule may be made to slide endwise over the arm either from below or above, or different forms of fastenings may be used to hold the arm closed.

65 The device above described enables an umbrella, parasol, or cane to be hung upon any support without difficulty, even in those cases where straight handles are used, which heretofore has, so far as I know, been impracticable. Hooked handles have been adapted to this use, 70 but not straight handles. By throwing the arm out in this case a hook is formed, and the rubber or other soft pad at the end allows the article to be hung upon a piano or upon fine furniture without danger of marring or scratching, and this pad causes the hook to adhere 75 without slipping, as before described.

Having thus described my invention, I claim—

80 The combination, with the handle A, of a pivoted arm, B, provided with a rubber or other soft pad, d, at its end, said arm being capable of expanding to form a hook to rest upon any support, and of closing into a cavity or socket in the handle, and being held by any 85 suitable retaining device, as herein shown and described.

In witness whereof I have hereunto signed my name in the presence of two subscribing witnesses.

GEO. W. HUGHES.

Witnesses:

R. F. OSGOOD,
H. S. BRIGGS.
